UNITED STATES PATENT OFFICE.

RUPERT HUGHES, OF THE UNITED STATES ARMY.

TRENCH-KNIFE.

1,315,503.

Specification of Letters Patent. Patented Sept. 9, 1919.

Application filed January 19, 1918. Serial No. 212,735.

To all whom it may concern:

Be it known that I, RUPERT HUGHES, a citizen of the United States, and a captain in the United States National Army, have 5 invented a new and useful Improvement in Trench-Knives, of which the following is a specification.

My invention relates to improvements in weapons, being more particularly an improvement in trench knives, and it consists 10 in the constructions, combinations and arrangements herein described and claimed.

An object of my invention is to provide a trench knife used in offensive and defensive 15 warfare, consisting principally of a knife blade mounted in a hasp and secured to the back of the hand by a strap, thus leaving the palm of the hand open with the fingers free to grasp an object.

Another object of the invention is to provide a trench knife constructed substantially 20 and mounted on the hand as described, including a blade latch with a button so disposed that it may be readily struck either 25 against the stock of the gun or the knee of the wearer, to cause the instantaneous extension of the blade.

Another object of the invention is to provide a knife as described designed upon the 30 new principle of effecting the drive through the downward blow of the arm, by securing the knife on the hand with an abutment for receiving the thrust, thus avoiding the necessity of gripping the knife in the palm 35 of the hand.

Another object of the invention is to provide a knife constructed and mounted on the new principle above outlined, in which the blade closes in a location out of reach of the 40 fingers, thus entirely removing the liability to accidentally catch and cut the fingers.

Other objects and advantages will appear 45 in the following specification, reference being had to the accompanying drawing in which

Figure 1 is a perspective view illustrating the trench knife in position and showing how an object may be grasped with the free palm.

Fig. 2 is a perspective view showing the knife in position and the strap for holding it in place.

Fig. 3 is a perspective view showing the

knife in position on the hand with the blade closed.

Fig. 4 is a side elevation of the knife, parts being shown in section.

Fig. 5 is a longitudinal section on the line 5—5 of Fig. 6.

Fig. 6 is a horizontal section on the line 60 6—6 of Fig. 5.

Fig. 7 is a cross section on the line 7—7 of Fig. 5; and

Fig. 8 is a detail view of the blade latch.

In carrying out my invention, I provide 65 a trench knife employing three principal elements in its construction. These elements consist of a hasp 1 arranged to be held on the back of the hand by a strap 2, with a knife blade 3 or any other suitable implement, pivoted at one end of the hasp.

The hasp 1 consists of two halves 4 and 5 which are secured together by the upper and lower sets of screws or rivets 6 and 7. The two halves are so shaped on top, that when 75 fitted together a blade recess 8 is formed. The blade 3 closes into this recess as shown in Fig. 3.

Here it may be mentioned that the implement employed in this connection, is not confined in use to the knife blade 3 illustrated in Figs. 1 and 2. This implement may consist of a spike of any size and shape suitable for the purpose for which it is intended. The shape of the blade recess 8 will be made to 85 conform to the particular type of implement used. When a knife blade is used, the recess will be relatively deep, and when a spike is used, the recess will be relatively shallow.

Pommels 9 and 10 are formed at the extremities of the hasp 1. These extend downwardly substantially as shown, leaving the interior surface of the hasp 1 rounded on a gradual curve so as to fit well upon the back 95 of the hand. The strap 2 formerly referred to, is now secured in place around the lower set of screws 7 thus closing the hand receiving part of the hasp, and providing a sure and flexible grip.

The construction of the strap is not confined to the use of leather such as illustrated in the drawing. Any other flexible material may be employed to equally good advantage. It is also conceivable that the 105 strap may consist of a metallic member,

although obviously, for the purpose of providing a strong, soft and flexible gripping member upon which the fingers of the hand may close, a leather strap is thought to be 5 more effective.

Referring again to the construction of the hasp, it will be observed in Figs. 4 and 7, that a strong projector spring 11 is secured at one end to one of the screws 6, in a chamber 12 formed in the member 4 of the hasp. 10 The other end of the spring 11 has an eyelet in which one end of a cable 13 is secured.

A sheave 14 receives the other end of the cable 13, and the end of the cable is secured 15 in the groove in any suitable manner. The sheave 14 is mounted on a blade carrier 15 which is square in cross section, and upon which the blade 3 is also mounted. The square carrier prevents the sheave and the 20 blade from turning with respect thereto, and to insure the fixture of the blade in position on the carrier, a pin 16 is fitted through the hub of the blade and the carrier.

The projector spring 11 is a contractile 25 spring and tends to rotate the sheave 14 in a clockwise direction in Fig. 4 to open the knife. The knife rocks on trunnions 17, which are rounded extensions of the square blade carrier 15, and are journaled in the 30 sides or halves 4 and 5 of the hasp 1. The construction of this portion of the invention is clearly illustrated in Fig. 6, where it will be seen, that the shoulders of the square blade carrier 15 abut the adjacent 35 surfaces of the sides of the hasp, and serve to space the adjacent portions of the hasp apart.

Movable beneath the end of the blade carrier 15 opposite to that on which the 40 sheave 14 is mounted, is the head 18 of a blade latch 19. The head 18 is adapted to be in contact with any one of the three surfaces of the square blade carrier 15 outside of the one directly adjoining the blade 3. 45 These three surfaces are indicated *a*, *b* and *c* in Fig. 5. The surface *c* is shown in contact with the head 18 with the blade 3 in the final or extended position. The engagement of the straight surface of the head 18 with 50 the straight surface *c* of the carrier, positively prevents the blade 3 from closing unless an extraordinarily powerful blow is delivered beneath the blade. Such a blow would tend to break the blade off entirely 55 rather than cause the square blade carrier to turn on the latch.

The blade is closed by pressing on the exposed button 20 mounted on the end of the latch shank 21 which carries the latch 60 19. A latch spring 22 normally keeps the button 20 in the exposed position, and holds the head 18 of the blade latch 19 in position beneath the blade carrier 15. On pressing upon the button 20 against the tension 65 of the spring 22, a rounded recess 23 ad-

jacent to the head 18 of the latch 19, is moved into position beneath the square blade carrier. The depth of this recess is sufficient to permit the corners of the blade carrier to turn, and so the blade may be closed into 70 the blade recess 8. Upon releasing the button, the latch will spring back, whereupon the surface *a* of the blade carrier will lie in contact with the head 18 and again prevent the blade from being turned on its trunnions until the button is again pressed. 75

Tension is stored in the projector spring 11 in turning the blade 3 over into the closed position, as just described. This tension in the spring becomes the motive power 80 in instantly extending the blade upon again pressing the button 20 to move the rounded recess 23 beneath the square blade carrier 15. It will be readily understood from Fig. 4 wherein the blade 3 is shown in the closed 85 position, that on releasing the blade carrier by moving the latch forwardly as just described, the tension of the spring 11 will cause the cable 13 to rotate the sheave 14 in a clockwise direction, and consequently 90 open the blade.

A recess 24 partly houses the latch spring 22 and provides an abutment for one end thereof. The recess 24 is formed on the rounded surface of the blade recess of the 95 member 5 of the hasp. The shank 21 is offset outwardly a short distance beyond the spring 22, the offset portion of the shank moving in a groove 25 in continuation of the recess 24. Abutments for limiting the 100 outward movement of the button 20 and consequently the inward movement of the latch 19, are provided by the offset formation of the groove 25 and by the rounded shoulder 26 in the member 5 adjacent to the 105 end of the latch 19.

A roughened end is provided on the button 20 by upsetting the end of the button on the end of the shank 21 which extends into the button. This roughened end is 110 useful in preventing slipping on quickly striking the button against the smooth gun stock when it is desired to quickly open the knife.

The operation of the trench knife is as 115 follows. One of the important features, if not the most important feature sought to be brought out in the present instance, is to provide a trench knife which is instantly accessible for use and at the same time may 120 be wielded to the best possible advantage, still leaving the palm of the hand open and the fingers free for other employment. Such other employment may consist of grasping, loading, aiming and firing a rifle. 125 From time immemorial, trench knives, as well as other knives, consisted of a blade with a handle adapted to be grasped in the palm of the hand with the fingers closing on the handle. 130

A permanent and firm grip is necessary to hold such a knife and deliver a powerful thrust with it. The trench knife hereinbefore described and illustrated in the drawing, does not necessarily call for a strong grip as a prerequisite to the successful use of the knife. There may even be instances where the grip or the power to grip of the wielder of the knife, may have become so weakened, that were it not for the fact that the knife is secured upon the hand in the new and novel manner herein disclosed, he would be utterly unable to employ this sort of a weapon.

15 So long as the user of the knife has power enough to raise his arm, he can employ the knife to good advantage, since in this instance the blow is delivered from the shoulder and muscular effort 20 ordinarily employed in tightening the fingers into a firm grip on the handle, is entirely unnecessary and avoided. It is even unnecessary to close the fingers on the strap 2. The palm of the hand may be left open 25 as in Fig. 2, when the kind of a blow delivered from the shoulder as just described, may be imparted.

The lower pommel 10, *i. e.*, the one adjacent to blade, becomes the element which 30 receives and delivers the whole thrust. The strap 2 simply holds the knife securely on the back of the hand. The second position of the blade 3 consists of moving the blade midway of the extreme positions with the 35 surface *b* of the blade carrier in contact with the head 18 of the latch, when the blade will stand at right angles to the hasp.

This position of the blade may be useful 40 in some instances. The hasp may be fixed upon the hand in a position opposite to that illustrated in the drawing when the button 20 will extend in the other direction. The particular position in which the knife is held, whether it be on the right or left 45 hand, is a matter determined more effectively by the user. It is to be emphasized however, that the underlying principle of the invention as hereinbefore repeatedly brought out, being to provide a trench knife 50 adapted to be mounted on the back of the hand, capable of being opened instantaneously for use, arranged to secure the drive through the pommel, and to leave the palm and fingers open and free for use.

55 While the construction of the knife as illustrated is that of a generally preferred form, obviously modifications and changes may be made without departing from the spirit of the invention or the scope of the 60 claims.

I claim:—

1. A weapon including a holder adapted to rest on the back of the hand to leave the palm open and fingers free, means carried 65 by the holder firmly engaging the sides of

the hand to enable the imparting of the force of a blow in wielding the weapon, means bridging said engaging means across the palm to retain the holder on the hand, normally retracted impaling means in the 70 holder, and actuating means including an engageable portion, arranged to extend said impaling means upon striking the engageable portion.

2. In a trench knife, a hasp, means for 75 securing the hasp upon the back of the hand, a blade mounted in the hasp, and means for extending the blade.

3. In a trench knife, a hasp, means for securing the hasp on the back of the hand, 80 a blade mounted in the hasp, and engageable means embodied in the hasp, arranged to instantaneously extend the blade upon engagement of said means.

4. A trench knife comprising a hasp 85 adapted to be held on the back of a hand leaving the palm and fingers free, means including pommels extending inwardly and firmly grasping the sides of the hand to enable the wielding of the knife, normally retracted impaling means mounted adjacent to one pommel, means carried by the hasp for extending the impaling means, and means exposed on the other pommel, holding the 90 extending means passive until struck. 95

5. In a trench knife, a hasp, means carried by the hasp engaging the palm and arranged to hold the hasp on the back of the hand, and a blade mounted in the hasp opening away from the user, to prevent accidental catching of the fingers between the 100 blade and the hasp in closing.

6. In a trench knife, a hasp, means for holding the hasp on the back of the hand to leave the palm free, a blade mounted in the 105 hasp, and means embodied in the hasp co-operating with the blade for holding the blade in different positions.

7. In a trench knife, a hasp, means for holding the hasp on the back of the hand, 110 a blade normally closed in the hasp, means for obtaining the extension of the blade, and means normally holding the extended blade from becoming accidentally closed.

8. In a trench knife, a hasp, means holding the hasp on the back of the hand to leave the palm open, a blade journaled in the hasp, arranged to assume the closed, open and intermediate positions, a non-circular portion embodied in the journal of the blade, and 115 a movable member adapted to contact certain of said non-circular portions to hold the blade in corresponding positions. 120

9. In a trench knife, a hasp, a blade capable of assuming the closed, open and intermediate positions, a journal bearing for the blade on the hasp, a non-circular portion embodied in said bearing, and a movable latch member including a straight portion engageable with certain of said non-circular 130

portions to hold the blade in the corresponding position and a recess adapted to be moved beneath the non-circular portion to permit turning of the journal bearing.

5 10. In a trench knife, a hasp arranged to be secured on the back of the hand, a blade mounted on and normally closed in the hasp, tension operated means for extending the blade, and a latch permitting operation of 10 said means to extend the blade, upon engagement.

11. In a trench knife, a hasp arranged to be secured on the back of the hand, a blade pivoted and normally closed in the hasp, and 15 means including an engageable releasing member and a tension operated device, for causing the blade to swing outward and away from the hand to the open position.

12. In a trench knife, a hasp, means for 20 securing the hasp on the back of the hand to leave the palm open, a blade mounted in the hasp in the normally closed position, tension operated means tending to open the blade, a latch engaging a portion of the 25 blade preventing said means from operating, and an exposed engageable member carried by said latch, said member being roughened to prevent slipping when striking a smooth surface.

30 13. In a trench knife, a hasp having a blade socket, a blade pivoted in the hasp and closing into the socket, tension operated means housed in the hasp to one side of the socket and coöperating with the blade 35 to open the blade, and a latch mounted on the hasp at the other side of the socket, normally engaging a portion of the blade at the pivot to prevent the blade from opening under the action of said tension operated 40 means.

14. In a trench knife, a hasp comprising half sections with removed portions at the top forming a knife socket when the sections are secured together, said sections including 45 extensions forming pommels for embracing the sides of a hand when the hasp is mounted on the back, a retaining member disposed

between the extremities of the pommels adapted to cross the palm of the hand, a knife blade pivotally mounted in the hasp 50 and closing into the socket, a non-circular portion included in the pivotal mounting, a latch located on one section and engaging one of the non-circular portions to keep the blade from turning, an exposed button carried by the latch for displacing it, and means carried by the other section for moving the blade on its pivotal mounting to the extended position upon displacement of the latch, said means including a contractile 60 spring and a flexible connection.

15. In a trench knife, a hasp, a blade, a pivotal mounting for the blade comprising a blade holder square in cross section and extending through the hub of the blade 65 with trunnions journaled in the hasp, a movable latch including a head normally engaging one of the surfaces of the blade holder to prevent turning, with a rounded recess movable beneath said holder to permit turning, a sheave mounted on the holder at the other side of the blade, and tension operated means for revolving the blade to the extended position on moving the rounded recess beneath said holder, said means including a spring with a cable attached to the sheave.

16. In a trench knife, a hasp including a half section with a recess and a groove terminating in a shoulder portion, a blade pivoted on the hasp and having a non-circular portion, a latch including a head with a rounded recess coöperating with said non-circular portion, said latch being adapted to abut said shoulder portion, a shank integral with the latch occupying the groove and the recess, a button on the end of the shank exposed on the end and upset to provide a roughened end and hold the button on the shank, and a spring occupying the 85 recess around the shank between the button and the end of the recess.

RUPERT HUGHES.
